UNITED STATES PATENT OFFICE.

GEORGE J. WINTER, OF BUFFALO, NEW YORK.

CUSHION ARCH-PROTECTOR SHOE.

Application filed August 20, 1926. Serial No. 130,484.

My present invention pertains to cushioned arch supports for shoes, in which the support is concealed and forms a permanent part of the shoe, whereby the foot is protected and will not become sore or calloused at the outer arch which is common in shoes in which a removable support is used.

The invention further contemplates the provision of a "built-in" arch support that automatically takes care of the always present movement of the arch of the foot of a wearer while walking, and the covering of the supporter so as to overcome any uncomfortable feeling to the foot were the supporter not provided with such covering.

Other objects and advantages will be fully understood from the following description and claim when the same are read in connection with the drawings accompanying and forming part of this specification, in which:

Figure 1 is a perspective view of the top covering or outer lining of soft leather of the finished insole.

Figure 2 is a similar view of the combined leather and lambswool layer of cushioning material immediately below the covering shown in Figure 1.

Figure 3 is a similar view of a layer of soft rubber ply that rests below the lambswool and immediately against the surface of the insole per se.

Figure 4 is a perspective view of an ordinary insole with my novel arch support secured therein.

Figure 5 shows the assembly of elements of Figures 1, 2 and 3.

Figure 6 is a view showing the assembly of Figure 5 secured on an insole equipped with the "built-in" arch support.

Figure 7 is an inverted view of Figure 6.

Similar numerals of reference designate corresponding parts in all the views of the drawings.

As shown in Figure 7, I use an ordinary Goodyear insole 8 having the ridge 9 and the usual covering 10.

I take this insole and punch three holes in the shank thereof. My arch support is preferably formed of metal or other suitable material and is preferably positioned on the insole shank and comprises a body portion 11. In the body portion I provide three countersunk openings, the one toward the heel portion being round and the forward and intermediate ones being oblong or elongated slots

12, the purpose of which will be apparent later.

The rivet 14 secures the arch supporter to the insole. Rivet 14 is formed after the manner of a cotter pin on its shank portions so as to be spread to grip the surface of a concavo-convex strip or backing plate 15 secured to the lower or other surface of the shank of the insole.

Rivets 13 similar to 14 are placed in the slots 12 and enter the slots 16 of plate 15. Manifestly upward and downward movement of the shank and hence the arch support will permit the backward and forward slight play or movement of the rivets, it being remembered that rivets 13 pass entirely through the insole.

To prevent injury and to present a comfortable surface to the foot of the wearer, I provide a covering for the upper surface of the insole and shank thereof as well as the arch support device. This cushioning device comprises a lower rubber ply or fabric 17 an intermediate member having an upper surface or backing 18 and lower lambswool 80 surface 19 and a top or upper surface 21 of soft glove-like leather that is cut with the wing portions 22. The ply 17 is cemented to the intermediate lambswool member and the upper lay of leather is secured to the said 85 elements by means of stitching 23. The openings 20 are formed in the intermediate elements to add to the comfort of the covering at the ball portion of the foot of the wearer.

The device or covering shown in Figure 5 is then stitched at 22 to the upper surface of the insole with the wing portion 22 overlapping or partially encasing the underside of the shank of the insole. Manifestly the wing portions 22 of covering 21 may be cemented to the shank on the underside thereof. Manifestly this construction of support is simple and inexpensive to produce and is materially advantageous and more comfortable than movable arch supports. It is concealed and comfortable and materially adds to the finished inside appearance of a shoe.

What I claim is:

In an arch support for shoes, the combination with an inner sole having a channel therein, and further having openings formed in the shank thereof, an arch supporter formed of a single piece of material and of concavo-convex form and further having two 110

elongated slots formed therein and an aperture formed therein, a reinforcing plate adapted to rest below the arch supporter, means for securing in fixed position one end of the supporter and plate, means for securing the supporter so as to permit backward and forward movements of a portion of the supporter with respect to the reinforcing plate, a protector covering adapted to rest on

the arch supporter and formed of rubber fabric and a felt and leather covering stitched in conjunction with the felt and rubber to the inner sole and having winged portions engaged by the welt, upper and inner sole of the shoe. 10

In testimony whereof I have hereunto set my hand. 15

GEORGE J. WINTER.
